ATTORNEY

UNITED STATES PATENT OFFICE.

HENRY D. JAMES, OF EDGEWOOD PARK, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

Application filed September 2, 1922. Serial No. 585,850.

My invention relates to systems of distribution and it has particular relation to motor control and the protection of switching apparatus employed in such systems. 5 The object of my invention is to provide means for preventing the opening of circuit-controlling devices while excessively heavy current is traversing the circuit.

It is customary to employ a knife switch 10 in the mainline circuit of a motor, together with a remotely-controlled switch of the contactor type for starting and stopping the motor. The main circuit may be interrupted by opening the knife switch but, 15 under certain load conditions, this operation is very undesirable on account of danger to the operator and probable destruction of the switch.

In one form of my invention, I employ 20 a latching mechanism that is controlled by the main current, for preventing the opening of the knife switch while the load current traverses the main circuit.

My invention will be described in connection 25 with the accompanying drawing, in which the single figure is a diagrammatic representation of circuits and apparatus embodying my invention.

Referring to the drawing, a motor, designated generally as 1, is connected through 30 a knife switch 2 and a contactor 3 to line conductors 4 and 5.

The knife switch 2 is provided with a latching mechanism comprising a latch 6, 35 a coil 7 and armature 8. A spring 9 normally maintains the armature 8 and hence, the latching mechanism in unlocked position. The armature 8 is pivotally mounted on an intermediate bearing.

40 A control switch 11 is arranged to complete a circuit for the operating coil of the contactor 3. When the switches 2 and 11 and the contactor 3 are closed, a circuit is completed from line conductor 4 through 45 coil 7, knife switch 2, motor 1 and contactor 3 to line conductor 5. The armature 8 is attracted to its closed or illustrated position, thereby latching the knife switch, when the latter occupies its closed position, 50 and preventing the opening thereof until the motor current has been reduced to a predetermined low value.

The motor 1 is controlled by means of the switch 11, which is located, as is customary,

at any convenient point, while the latching 55 device eliminates the danger of opening the switch 2, as is sometimes done in an emergency, or inadvertently, prior to the opening of contactor 3.

Although I have illustrated my invention 60 in preferred forms, various modifications may be made in details and general arrangement without departing from the spirit and scope of my invention, and I desire, therefore, to be limited only by the scope of the 65 appended claims.

I claim as my invention:

1. The combination with a motor and a circuit interrupting switch therefor, of an additional switch for interrupting the motor 70 circuit and means comprising a series coil for preventing the operation of said additional switch prior to the operation of the first switch.

2. The combination with an electric circuit and a remotely controlled circuit-interrupter therefor, of a manually operable switch for also controlling said circuit means for latching said switch in its closed position and a coil responsive to load conditions of said circuit for rendering said latching means effective to prevent opening said switch prior to operation of said circuit interrupter. 75

3. The combination with a translating device and a controlling device therefor having an operating coil connected in parallel-circuit relation to said translating device, of a second controlling device having a coil connected in series-circuit relation with said 80 translating device and being effective to prevent the operation of said second controlling device to interrupt the flow of current through said translating device. 85

4. The combination with a translating device and a switch connected in circuit therewith, of a latch, means for normally biasing said latch to a position permitting the opening of said switch, and a coil connected in series-circuit relation with said translating 90 device for operating said latch to a position to prevent the opening of said switch while current is flowing therethrough. 95

In testimony whereof, I have hereunto subscribed my name this 30th day of August, 1922. 105

HENRY D. JAMES.
